UNITED STATES PATENT OFFICE.

GRANT HAMMOND, OF HARTFORD, CONNECTICUT, ASSIGNOR TO DALTON ARMS CORPORATION, OF NEW YORK, N. Y., A CORPORATION OF NEW YORK.

FIREARM.

1,294,452.

Specification of Letters Patent. Patented Feb. 18, 1919.

Application filed April 24, 1915. Serial No. 23,584.

To all whom it may concern:

Be it known that I, GRANT HAMMOND, a citizen of the United States, residing at Hartford, in the county of Hartford and 5 State of Connecticut, have invented a new and improved Firearm, of which the following is a specification.

My invention while not limited in its application is of especial advantage in connection with that class of firearms that are discharged while supported by and against the shoulder of a person, and an object of my invention, among others, is to provide a firearm of this class that shall be extremely 10 simple and cheap in construction and durable and effective in operation.

One form of firearm embodying my invention and in the construction and use of which the objects herein set out, as well as others, 15 may be attained, is illustrated in the accompanying drawings, in which—

Figure 1 is a top plan view of a portion of a firearm embodying my invention.

Fig. 2 is a view in central longitudinal 20 section through that part of the firearm shown in Fig. 1.

Fig. 3 is a sectional rear view through the receiver of my improved firearm, on plane denoted by dotted line 3—3 of Fig. 1.

30 Fig. 4 is a detail view illustrating the breech-bolt and breech-bolt sleeve, the latter being cut in section to show construction.

Fig. 5 is a detail view in cross section through the receiver on plane denoted by 35 dotted line 5—5 of Fig. 1.

Fig. 6 is a bottom view of the breech-bolt, with parts broken away.

Fig. 7 is a view in cross section through the device on plane denoted by dotted lines 40 7—7 of Fig. 2.

Fig. 8 is a detail top view of the rear portion of the receiver, the front part being broken off.

Fig. 9 is a detail rear view of the receiver. 45 Fig. 10 is a detail view in cross section through the breech-bolt and contained parts just back of the actuating handle.

A mount is shown in the accompanying drawings, which mount comprises the stock 50 10 and fore end 11 of a firearm embodying my invention and which mount may be constructed of wood as is usual in devices of this class and which is recessed to receive the metallic parts of the gun, which parts 55 in the present instance include a receiver 12

and a trigger plate 14, said receiver having a barrel 13 secured thereto and the trigger plate being secured to the barrel as by means of screws 15. The trigger plate has, preferably formed integral therewith, a 60 magazine 16 extending upwardly through the frame and formed to register with an opening 17 in the bottom part of the receiver and which opening is in vertical alinement with a discharge opening 18 in 65 the top and side of the receiver. A bore 19 extends from the discharge opening to the front of the receiver, this bore being preferably threaded to receive the threaded end of the barrel, and back of this threaded portion an annular breech-bolt locking groove 20 is formed with breech-bolt releasing grooves 21—22 extending from the locking groove backwardly to the rear end of the receiver, the releasing groove 22 being 70 intersected or interrupted by the discharge opening 18.

A breech-bolt 23 is located in the bore 19, extending in its closed position across and closing the discharge opening. This 80 breech-bolt constitutes an important element of my invention, special attention being given to its construction to enable it to be formed in an economical way. This bolt is of cylindrical form throughout the 85 greater part of its length, that enables it to be readily turned to shape with an annular groove 24 for the reception of an extractor strap intermediate its ends and a reduced portion 25 at its rear end. The bolt thus 90 formed may be made upon a screw or automatic machine, and a single tool is employed to cut away the bolt on opposite sides at its forward end, leaving enough of the original metal to constitute locking lugs 95 26 that are formed to fit the annular locking groove 20 and the releasing grooves 21—22, these lugs 26 being relieved or beveled on one edge as at 27 to permit a slight rearward movement of the breech-bolt before the lugs fully register with the releasing grooves, and also to permit the lugs to readily engage with the locking grooves in a locking movement of the breech-bolt.

A breech-bolt sleeve 28 is secured to the 105 rear end of the breech-bolt as by means of interengaging screw threads, this sleeve having a threaded recess 29 to receive the end of the breech-bolt, the latter being rotatable to a limited extent within this re- 110

cess. A recess 30 for the reception of the neck of the head of the firing pin extends inwardly from the rear end of the breech-bolt sleeve, the inner end of said neck resting against the bottom of this recess, and a firing pin opening 31 extending between the recesses 29 and 30, a slot 32 through the bottom of the breech-bolt sleeve at this end also cutting into these recesses.

10 A breech-bolt actuating handle 33 is secured to the breech-bolt as by means of a strap 34 extending around said bolt and resting against a shoulder 35 formed by the reduced rear end of the bolt, this strap and handle being held in place in any suitable manner, in the construction herein shown a pin 36 extending through the strap and across a groove in the breech-bolt as shown in Fig. 5 of the drawings.

20 The breech-bolt has a central opening 38 to receive a firing pin, the latter being formed in two parts including a main part 37 and firing tip 39, the latter being pointed at its front end to engage a cartridge shell 25 and having a head 40 at its rear end located within the enlarged part of the central opening, as shown in Fig. 2 of the drawings. The reduced part of the firing tip at the back of said head and the forward end of 30 the main part of the firing pin are "halved" together, these halved portions having a registering lug and groove to lock them together and a locking sleeve 41 surrounding these parts holds the lug and groove in engagement, as shown in Fig. 2 of the drawings. A firing pin spring 43 is located in the enlarged part of the firing pin opening, thrusting with one end against the locking sleeve 41 and with the opposite end against

40 a bushing 44 located at the mouth of the firing pin opening and resting against the bottom of the threaded recess 29. A firing pin head 45 is secured to the end of the firing pin in any suitable manner, in the 45 construction herein shown the end of the pin being threaded for this purpose. A neck 46 projecting from the head has a cocking prong 47 located in the slot 32, the forward end of this prong being beveled to engage 50 the beveled part 48 of the end of the breech-bolt. The cocking prong is also provided with a cocking shoulder 49 located in position to be engaged by a sear 50 pivotally mounted and located in a slot extending 55 through the bottom of the receiver at its rear end. A trigger 51 is slotted at its upper end within which slot the sear 50 is located, a pivot pin 52 extending through the side parts of the trigger thus formed 60 and pivotally connecting it to the sear. These side parts of the trigger are provided with an initial bearing 53 and a disengaging bearing 54, the former being located nearest the pivot 52 first engaging the frame 65 and serving to impart initial movement to

the sear with a certain amount of power transmitted from the trigger, and the latter engaging the frame just before the sear becomes disengaged from the shoulder 49 acting at the time of disengagement of the 70 sear from said shoulder and requiring a little more power to be applied from the trigger than at the initial movement of the sear. This multiple fulcrum enables the greatest amount of power to be applied at 75 the time of initial movement of the sear, and up to nearly the point of disengagement of the sear from the firing pin, and at the time of disengagement of said parts, and when less power is required to disengage them the second fulcrum is brought into action. This multiple fulcrum enables the operator to know when the point of disengagement of the sear and firing pin has been nearly reached by apprising him 80 through the "feeling" of the trigger when the second fulcrum comes into action.

The bottom 55 of the magazine is held in place by a lip 56 on its front edge engaging a groove 57 in the trigger plate, a magazine holder 58 retaining the parts thus engaged. This holder is movably located in a well 59 in the rear wall of the magazine, a pin 60 permitting a limited movement of the holder within the well. A releasing prong 61 is formed on the end of the holder and projects beyond a stop shoulder 62 formed within the mouth of the well 59, the length of this prong being such that when an instrument is placed against it to push it inward and in such movement the projecting edge of the instrument strikes the stop shoulder 62, the end of the main part of the holder will have been moved inward far enough to enable movement of the bottom 100 55 and disengagement of the lip 56 from its groove. The holder 58 is retained in its holding position as by a spring 63 which also presses against an ejector 64 in the opposite end of the well 59. This ejector 110 has a reduced or flattened portion 65 adapted to pass into a slot 66 in the forward end of the breech-bolt and back of a cartridge shell to eject the latter, as the breech-bolt moves backwardly. A pin 67 may be employed to limit the extent of movement of the ejector.

A breech-bolt stop 68 is movable longitudinally within an opening in the rear end of the receiver, a releasing notch 69 extending across the stop permitting passage of one of the locking lugs 26 when said stop is moved inward as by pressure of a thumb or finger upon its outer end and within a depression 70 surrounding the mouth of the opening in the receiver. A spring located underneath the stop, and upon which the latter is seated, retains the holder in the position shown in Fig. 5, to prevent removal of the breech-bolt and a pin 71 secured with 120 125 130

in the receiver and projecting through a cut-away portion in the side of the holder limits its movement.

An auxiliary breech-bolt holding lug 72 is formed upon the strap of the handle 33 in position to be turned into a breech-bolt holding recess 73 formed in the bore in the receiver, the lug being passed into said recess when the breech-bolt is pushed forward 10 and the handle is turned downwardly to secure the breech-bolt in its closed position.

A cam 74 is formed on the rear edge of the receiver in position to be engaged by the handle 33 when the latter is swung upwardly to unlock the breech-bolt, the action 15 of this cam together with the handle starting the movement of the cartridge shell from the rear end of the barrel, and should said shell stick the force of this action is such as to certainly start such movement with the application of little power, the beveled portion 27 on the rear edges of the locking lugs enabling this starting movement of the cartridge shell to take place. The 20 cam 74 terminates at a shoulder 75 on the receiver that limits the rotating movement of the breech-bolt with the locking recess 76 therein in position to receive the breech-bolt locking pin 77 having a bearing projection 25 78 located in contact with the side of the breech-bolt, or, as shown herein, with the strap 34 and within which the recess 76 is formed. A safety locking pin 79 is located in a hole 80 extending through the breech- 30 bolt sleeve, this hole also containing the breech-bolt locking pin 77. The hole 80 is of different diameters to receive the pins 70 and 79, the latter having a recess on its inner end to receive the former, and a spring 35 81 is located in recesses in both of said pins to press them apart, a pin 82 secured within the breech-bolt locking sleeve extending 40 through a notch in the side of the pin 77 to limit its sliding movement. The pin 79 45 is shouldered at its inner end to provide a safety locking prong 83 adapted to be turned into a safety locking slot 84 in the end of the breech-bolt, and in the threaded portion, as shown in Fig. 4 of the drawings.

50 A safety locking collar 85 is removably secured to the pin 79 as by means of a locking screw 86. This collar projects through a slot 87 in the side of the breech-bolt sleeve and it is cut-away on one side as at 88 sufficiently to receive the side of the neck 46 of the firing pin head. A thumb piece 89 projects from one side of the collar and preferably extends along the side of the breech-bolt sleeve that constitutes a bearing therefor, this pin serving as a means for actuating 55 the safety locking member. When in the position shown in Fig. 7 the firing pin may be moved backwardly within the breech-bolt. When moved to the position 60 shown in dotted lines in Fig. 3 the collar

will be turned into the path of movement of a shoulder 90 on the firing pin head. This can, however, only be done when the firing pin is moved back and when the collar is thus turned the firing pin will be held 70 in such position that it can not strike a cartridge primer. When the safety locking pin 79 is turned further in this same direction so that the thumb piece will be located in the uppermost position shown by dotted 75 lines in Fig. 3, the prong 83 will be located in the safety locking slot 84 in the breech-bolt and the breech-bolt sleeve and breech-bolt will thus be locked against relative turning movement. 80

It will thus be seen that with the safety locking mechanism the breech-bolt and breech-bolt sleeve may be locked together with the breech-bolt in its closed position so that the latter can not be moved, or the 85 firing pin may be locked so that it can not operate to fire a cartridge.

As the breech-bolt is turned to open position the handle 33 will strike the shoulder 75, the breech-bolt turning within the 90 breech-bolt sleeve and the left-handed screw thread between the parts operate to move the sleeve slightly backward away from the breech-bolt.

When the breech-bolt is closed and the 95 handle turned to locked position then the operation of the screw thread will be such as to draw the sleeve against the end of the breech-bolt.

A spring seated detent 91 is located in the 100 thumb piece 89, projecting from that edge lying next to or against the breech-bolt sleeve and in position to engage recesses within the outer surface of the sleeve to yieldingly hold the thumb piece and safety 105 locking pin 79 in the several positions denoted in Fig. 3.

While I have shown and described herein a satisfactory construction of mechanism for accomplishing my purpose, this construction 110 may be changed to a greater or lesser degree without departing from the spirit or intent of the invention which is, therefore, not limited to the exact construction herein shown and described. 115

I claim—

1. A firearm including a receiver having a cylindrical opening therein with a discharge opening therefrom and a locking groove at the end of said cylindrical opening, a 120 breech-bolt located in said opening and of cylindrical shape for substantially its whole length, locking lugs projecting from the side of the bolt from the forward end thereof, an actuating lever secured to the bolt, a reduced 125 threaded portion of round form in cross section at the rear end of the bolt, and an interiorly threaded breech-bolt sleeve fitting over and receiving the threaded end of said bolt. 130

2. A firearm including a receiver having a breech-bolt opening of cylindrical form therein with a discharge opening therefrom and a locking groove located at the end of 5 said cylindrical opening, a breech-bolt located in said opening and of cylindrical form for substantially its whole length, locking lugs extending from the side of the breech-bolt at its forward end, a reduced portion of 10 round shape in cross section located at the rear end of the breech-bolt, part of said reduced portion being threaded, an actuating lever secured to said reduced portion, and an interiorly threaded breech-bolt sleeve 15 fitting over and receiving said threaded portion.

3. A breech-bolt mechanism for a firearm including a breech-bolt sleeve having recesses extending from opposite ends with a dividing wall between them, one of said recesses being threaded, a breech-bolt fitting within said threaded recess, a firing pin located within the breech-bolt and extending through the wall between the recesses, and 20 25 a firing pin head secured to the firing pin and extending into the other of said recesses.

4. A firearm including a receiver having a breech-bolt opening therein with a locking groove at the inner end of said opening, 30 a discharge opening, a breech-bolt located within the breech-bolt opening and having locking lugs engaging said groove and a threaded end, a breech-bolt sleeve having a threaded recess that receives the threaded 35 end of the breech-bolt, said sleeve also having a recess for a firing pin head, a firing pin located in the breech-bolt and projecting through the bottom of said threaded recess, a firing pin head located in its recess and 40 having a part projecting through a slot extending through the wall of the breech-bolt sleeve into said recess, means for actuating the breech-bolt, and means for actuating the firing pin.

45 5. A firearm including a receiver having a breech-bolt opening therein with a locking groove at the end of said opening and a discharge opening therefrom, a breech-bolt located within said opening and having locking lugs to engage said groove and a threaded end, a breech-bolt sleeve having a threaded recess that receives the threaded 50 end of the breech-bolt, a firing pin within the breech-bolt extending through said sleeve, a firing pin head secured to said firing pin, and a locking member secured in 55 said sleeve to hold the firing pin in a retracted position.

6. A firearm including a receiver having a 60 breech-bolt opening therein with a locking groove at the end of said opening and a discharge opening therefrom, a breech-bolt located within said opening and having locking lugs to engage said groove and a threaded end, a breech-bolt sleeve having a thread- 65

ed recess that receives the threaded end of the breech-bolt, a firing pin within the breech-bolt extending through said sleeve, a firing pin head secured to said firing pin, and a locking member secured in said sleeve 70 to lock the breech-bolt against rotation.

7. A firearm including a receiver having a breech-bolt opening therein with a locking groove at the end of said opening and a discharge opening therefrom, a breech-bolt located within said opening and having locking lugs to engage said groove and a threaded end, a breech-bolt sleeve having a threaded recess that receives the threaded end of the breech-bolt, a firing pin within the 80 breech-bolt extending through said sleeve, a firing pin head secured to said firing pin, and a locking member secured in said sleeve to hold the firing pin in retracted position and the breech-bolt against rotation. 85

8. A breech-bolt mechanism including a breech-bolt and a sleeve rotatably secured together, a safety locking member to secure the breech-bolt and sleeve against independent rotation and having a recess, a locking member located within said recess within the safety-locking member and adapted to lock the breech-bolt and sleeve together during rearward movement of the breech-bolt but to release said members in the forward 90 position of the breech-bolt, and means for actuating the breech-bolt. 95

9. A breech-bolt mechanism including a breech-bolt and a breech-bolt sleeve rotatably connected, a safety locking member located in the breech-bolt sleeve to lock the sleeve and breech-bolt against independent rotation, a locking member projecting into the safety locking member and adapted to lock the breech-bolt and sleeve against independent rotation during backward movement of said parts but to release them in their forward position, and means for operating the safety locking member. 100 105

10. A breech-bolt mechanism including a breech-bolt and a breech-bolt sleeve rotatably connected, a safety locking member located within a recess in the sleeve to lock the breech-bolt and sleeve against independent rotation, a locking member located 110 in said recess to lock the sleeve and breech-bolt in their backward movement but to release them in their forward position, a spring located in a recess in each of said locking members, and means for operating 115 the safety locking member. 120

11. A firing pin composed of two parts "halved" together at one end and with a projection on one of said halved portions entering a recess on the other of said halved 125 portions, and a sleeve surrounding said sections to lock them together.

12. A firing pin including two sections each cut away for half its diameter at one end to "halve" the two parts together, one 130

of said sections having a head, a projection on one of said halved parts to fit a recess on the opposite halved part, and a sleeve fitting over said sections and against said head to 5 hold the sections in locked engagement.

13. A breech-bolt mechanism including a breech-bolt having a central opening therein, a firing pin located within the breech-bolt and including two sections "halved" together within the breech-bolt, said halves having one a projection to fit within a recess in the opposite half and a sleeve surrounding said firing pin sections within the breech-bolt, a firing pin spring thrusting 15 with one end against said sleeve and the opposite end against a shoulder within the rear end of the breech-bolt, and means for operating the breech-bolt.

14. A breech-bolt mechanism for a fire- 20 arm including a breech-bolt having a recess at one end, a cam surface forming one wall of said recess, said bolt having lock-

ing lugs at its opposite end, a breech-bolt sleeve attached to the breech-bolt by inter-engaging screw threads, and a firing pin located within the breech-bolt and having a 25 prong projecting into said recess to be acted upon by the cam surface thereof.

15. A firing mechanism for a firearm including a breech-bolt having locking lugs at 30 one end and a reduced threaded portion at the opposite end, an operating handle located upon said reduced portion that is threaded at its outer end, and a breech-bolt sleeve having an interiorly threaded recess 35 to engage said breech-bolt, said handle being attached to the bolt within the annular recess between the body of the bolt and the breech-bolt sleeve.

GRANT HAMMOND.
